UNITED STATES PATENT OFFICE.

THOMAS W. HOLT, OF ELKHART, INDIANA, ASSIGNOR, BY MESNE ASSIGNMENTS, TO THE ADAMS & WESTLAKE COMPANY, OF CHICAGO, ILLINOIS, A CORPORATION OF ILLINOIS.

SASH LATCH.

Application filed June 1, 1925. Serial No. 34,001.

This invention has to do with latches of the type which are adapted to be associated with window sashes for the purpose of holding the sashes in raised positions.

5 The object of the invention is to provide a sash latch of improved construction which may be easily and compactly assembled with a sash, which is so reinforced as to withstand the most severe usage, and which may 10 be manufactured at relatively small cost.

Other objects and advantages of the invention will be evident upon a full understanding of the nature of the sash latch; the invention residing substantially in the features 15 of construction and arrangement hereinafter disclosed.

In order that the invention may be readily understood, one preferred embodiment of the same is presented in the accompanying 20 drawings and in the following description based thereon, but it will be appreciated that the invention is susceptible of embodiment in other structurally modified forms, and the particular form chosen for exemplification 25 is therefore not to be construed as limiting the application of the invention short of its intended scope as set forth in the appended claims.

In the drawings—

30 Fig. 1 is an inside view of one corner of a sash equipped with the latch of the invention;

Fig. 2 is a somewhat similar view, but with the front face of the latch plate broken away to show the contained parts;

Fig. 3 is a vertical section through the sash taken in the median plane of the same;

Fig. 4 is a vertical section taken on the line 4—4 of Fig. 3;

Fig. 5 is a vertical section taken on the line 5—5 of Fig. 3;

Fig. 6 is a horizontal section taken on the line 6—6 of Fig. 3;

Fig. 7 is a view corresponding to Fig. 1, but showing a slightly different way of mounting certain of the latch parts; and

Fig. 8 is a vertical section taken on the line 8—8 of Fig. 7.

The latch of the invention is shown in the drawings as applied to a sash 10 of sheet metal construction. The latch, which may be readily assembled with, or removed from, the sash, has the parts thereof mounted upon two detachable members. One of such mem-

bers is an L-shaped corner piece 11 contained within the mitered ends of the stile 12 and rail 13 of the sash, and the other is an L-shaped latch plate 14 secured to the side walls of and spanning the mitered ends of the stile and rail.

The corner piece 11, when used with hollow sheet metal sash members of the particular cross-sectional form shown, is preferably in the form of two flat L-shaped side plates 15 which are arranged in spaced relation to each other against the flat parallel side walls of the sash members, as shown in Figs. 4, 5 and 6. The plates 15 of the corner piece are joined together along their long vertical edges by an integral cross web 16 which seats 70 against the grooved edge wall 17 of the stile 12, and the edge portions of the plates 15 most removed from the web 16 are provided with inturned tongues 18' which abut each other for the purpose of maintaining 75 such portions in properly spaced relation.

A block 18 of metal is secured between the ends of the vertically extending portions of the side plates 15 by a rivet 19 or other suitable means, and the lower end of the block 18 is bifurcated to provide two spaced ears 20. A detent 21 is pivotally mounted at its upper end between the ears 20 on a tubular pin 22 which is supported in the ears, and the depending stop-engaging nose 23 of the detent is adapted to oscillate into and out of the guide groove of the stile 12 through two aligned apertures 24 formed in the web 16 of the corner piece and the wall 17 of the stile. The nose 23 of the detent 21 is adapted to pass out over and seat upon a horizontal ledge presented by a stop, and many types of stops may be employed in conjunction therewith. The particular stop 25 shown is embodied in a combined sash 90 guide, weather strip and latch rack, forming the subject matter of a separate application. A leaf spring 26 is secured at its lower end by a rivet to the bottom of the cross web 16 of the corner piece, and the upper 95 end of the spring is reduced in width at 27 and bears against a grooved portion 28 of the detent 21 in a direction tending to urge the nose of the detent outwardly into its stop-engaging position, as shown in Fig. 3. The upper end of the detent may be advantageously arranged in substantial contact 100 with the block 18 at a point 29 between the

ears 20, in order that, whenever the nose of the detent is brought to rest abruptly by the stop, the stresses to which the detent is subjected will be transmitted directly to the block as a back stop rather than to the necessarily small pivot pin 22 about which the detent oscillates.

The latch plate 14 previously referred to is flanged about its edges at 30 to form a 10 housing, and is arranged with the flanges against the side walls of the stile and rail. A finger piece 31 is pivotally mounted within the latch plate 14 at 32, and is provided with a laterally extending pin 33 which 15 passes through two aligned apertures 34 in the corner piece and stile into an aperture 35 in the detent. When the detent is in its stop-engaging position, the finger piece 31 connected therewith by the pin 33 is in the 20 position shown in Fig. 2. A wire spring 36 is also carried within the latch plate 14, and bears against a grooved shoulder portion of the bottom of the finger piece in such a way as to hold the same in the position shown. 25 The spring 36 may be held in position in the latch plate by means of a reversely bent tongue 37 inside of the latch plate on the lower horizontal flange 30 of the plate. The upper horizontal flange 30 of the latch plate 30 is reversely bent outside of the plate to provide a horizontal lift 38 for use in raising the sash.

The corner piece 11, stile 12, rail 13 and latch plate 14 are detachably secured to 35 together by means of a plurality of transfixing screws. Two screws 39 and 40 may pass through aligned apertures in the latch plate, stile and corner piece, and engage within the tubular pivot pin 22 upon which the detent 40 21 is mounted, and two telescopic clamp screws 41 may pass through aligned apertures in the latch plate, rail and corner piece.

It will be appreciated from the foregoing 45 description that the various parts of the latch of the invention may be permanently mounted separate from the sash, and may then be assembled with the sash in proper relation to each other by merely telescoping 50 the ends of the corner piece 11 into the mitered ends of the stile and rail, placing the latch plate in position against the corner of the sash and securing the assemblage together with the screws 39, 40 and 41. It 55 will be observed that both the detent and the finger piece of the latch are independently actuated by separate springs, which insures proper actuation of the latch even though one of the springs be rendered inoperative 60 for any reason. The extremely simple construction of the parts of the latch and of the members upon which such parts are mounted permits the latch to be manufactured and assembled at low cost.

In Figs. 7 and 8 of the drawings is shown

a slightly modified form of the latch which differs from the form above described principally in the way in which the detent 21 is mounted. In this form a stud 42 is fixedly secured to the latch plate 14 at a point above 70 the finger piece 31. The detent 21 is pivotally mounted on the stud 42 in lapped relation to the finger piece 31, and is oscillated in a stop-engaging direction by means of a suitably anchored coil spring 43 which 75 encircles the stud between the detent and the plate. All of the parts of the latch are, as a consequence, completely assembled with the latch plate 14 separate from the sash to which the latch is adapted to be attached, 80 and the latch assembly may be readily associated with the sash by merely cutting an opening 44 in the side wall of the sash and the corner piece, inserting the detent and stud through such opening until the detent 85 is in the median plane of the sash and in line with the opening 24, and then fastening the latch assembly in place with the two telescopic clamp screws 41 and a short screw 45 which may extend into the free end of the 90 stud 42.

I claim:

1. In a sash latch, a detent, a spring tending to move the detent into its stop-engaging position, a finger piece connected with the 95 detent to move the latter out of its stop-engaging position, and a second spring tending to move the finger piece in such a direction that the detent will be moved thereby into its stop-engaging position.

2. In a sash latch, a sash member, a detent housed within the sash member, a latch plate secured to one side of the sash member, and a finger piece carried by the latch plate exteriorly of the sash member and connected with the detent through an aperture in the 100 sash member.

3. In a sash latch, a hollow sheet metal sash member, a detent mounted within the sash member for movement in a plane of the sash, a hollow latch plate detachably secured to one side of the sash member, and a finger piece carried by the latch plate exteriorly of the sash member for movement in a plane substantially parallel to that of the detent and detachably connected with the detent through an aperture in the sash member.

4. In a sash latch, a sash member, a latch plate having its edges flanged toward the sash member to form a housing, and a finger piece mounted within the latch plate, one of the flanged edges of the latch plate being reversely flanged on the outside of the plate to form a lift below the finger piece.

5. In a sash latch, two sash members arranged to form a sash corner, an L-shaped latch plate having its edges flanged toward the sash members at the corner to form a housing, and a finger piece pivotally mounted within the vertically extending portion of 125 130

- the latch plate, one of the flanged edges of the horizontally extending portion of the latch plate being reversely flanged outside of the plate to form a lift below the finger piece. 5
6. In a sash latch, two hollow sheet metal sash members arranged to form a sash corner, a corner piece housed within the sash members at the corner, a latch plate spanning the sash members at the corner, means 10 for securing the corner piece, sash members and latch plate together, a detent carried by the corner piece and operable through an aperture in the outer wall of the adjacent sash member, and a finger piece carried by the 15 latch plate and connected with the detent through an aperture in the side wall of the sash member. 7. In a sash latch, a hollow sheet metal stile having an aperture in the outer wall 20 thereof, a lining member contained within the stile, a detent pivotally carried by the lining member in a position for movement through the aperture in the stile, and means for operating the detent. 8. In a sash latch, a hollow sheet metal stile having an aperture in the outer wall thereof, a lining member contained within the stile, a detent pivotally carried by the lining member in a position for movement 30 through the aperture in the stile, means for operating the detent, and a block carried by the lining member in approximate contact with the detent when the latter is in its stop-engaging position whereby to provide a back 35 stop for the detent supplemental to its pivot. 9. In a sash latch, a detent having a pivotal mounting, a finger piece arranged in lapped relation to the detent and having a pivotal mounting axially separate from that of the 40 detent, and a laterally extending connection between the lapped portions of the detent and the finger piece to permit positive operation of the former by the latter in either direction. 10. In a sash latch, a detent having a pivotal mounting, a finger piece having a pivotal mounting axially separate from that of the detent, and a connection between the detent and the finger piece to permit operation 50 of the former by the latter, said connection comprising a pin extending laterally from one of the elements and engaging in an aperture in the other. 11. In a sash latch, a hollow sheet metal 55 stile having two apertures in the outer and side walls thereof, a latch plate spanning the aperture in the side wall of the stile and secured to the stile, a detent pivotally carried by the latch plate and inserted through the 60 aperture in the side wall of the stile into a position in alignment with the aperture in the outer wall thereof, and a finger piece also pivotally carried by the latch plate and connected with the detent to operate the latter. 12. In a sash latch, a hollow sheet metal 65 sash member, a latching bolt contained within the hollow portion of the member, a plate secured against one side of the member, and a finger piece carried by the plate between the same and the member and operatively connected with the bolt through an aperture in the member. 70
13. In a sash latch, a sheet metal sash member, a latching bolt arranged within the member and pivotally mounted thereon, 75 a housing plate secured against and opening toward one side of the member, a finger piece arranged partly within the plate and pivotally mounted thereon, and a laterally separable operating connection between the 80 finger piece and the latching bolt passing through an aperture in the side of the member within the area of the plate. 14. In a sash latch, two sheet metal sash members arranged to form a sash corner, an 85 interior reinforcing member extending into both sash members at the corner, a movable latching bolt carried by the reinforcing member, an exterior plate spanning both sash members at the corner, a movable finger 90 piece carried by the plate, and a lateral connection between the finger piece and the latching bolt for operating the latter. 15. In a sash latch, two sheet metal sash members arranged to form a sash corner, an 95 interior reinforcing member extending into both sash members at the corner and having two laterally spaced L-shaped side portions in engagement with the inner sides of the members, a latching bolt pivotally mounted 100 on the reinforcing member within the sash corner, an exterior plate spanning both sash members at the corner and having a finger lift, a finger piece pivotally mounted on the plate and extending into a position above 105 the lift, and a lateral connection between the finger piece and the latching bolt for operating the latter. 16. In a sash latch, two sheet metal sash members arranged to form a sash corner, 110 one of said members having an aperture in one side thereof, an interior reinforcing member extending into both sash members at the corner and having two laterally spaced L-shaped side portions in engagement with the inner sides of the member, one of said side portions having an aperture 115 therein in register with the aperture in one of the sash members, a latching bolt arranged between the upper side portions of the reinforcing member and having an aperture in register with but of less extent than the aperture in one of the sash members, a pivotal connection between the upper end of the latching bolt and the adjacent portions of the reinforcing member, an exterior plate spanning both sash members at the corner and having a finger lift, a finger piece pivotally mounted on the plate and extending 120 into a position above the finger lift, a ready- 125
- 130

ly separable lateral connection between the finger piece and the latching bolt for operating the latter, and a spring interposed between the finger piece and the plate for 5 maintaining the former normally with the latching bolt in stop-engaging position.

17. In a sash latch, a sash member, a latching bolt arranged therein, a plate secured to one side of the sash member adjacent the latching bolt, a finger piece pivoted to the plate, an extension on the finger piece, a laterally extending connection between the extension and the latching bolt for moving the latter upon oscillation of the 10 finger piece, a shoulder on the finger piece, and a spring interposed between and acting in opposite directions against the shoulder and a portion of the plate.

18. In a sash latch, a sash member, a latching bolt arranged within the sash member and pivotally mounted therein, a plate secured to one side of the sash member adjacent the latching bolt and having a finger lift, a finger piece arranged between 15 the plate and the sash member and pivotal-

ly mounted on the plate, an extension on the finger piece, a laterally extending lug on the extension projecting into an aperture in the latching bolt below the pivotal axis thereof for moving the lower end of the bolt into and out of stop-engaging position, a shoulder on the finger piece formed to center a spring, and a spring interposed between and acting in opposite directions against the shoulder and a portion of the plate.

19. In a sash latch, a detent, a spring tending to move the detent into its stop-engaging position, a finger piece connected with the detent to move the latter either into or out of its stop-engaging position, and a second spring tending to move the finger piece in such a direction that the detent will be moved thereby into its stop-engaging position independently of the action of the first spring.

In testimony whereof I have hereunto subscribed my name.

THOMAS W. HOLT.
